PAPER FEEDING DEVICE

Elmer H. Dreher, Brooklyn, N. Y., assignor to
Remington Rand Inc., Buffalo, N. Y., a corpora-
tion of Delaware

Application April 21, 1934, Serial No. 721,664

2 Claims. (Cl. 197—138)

This invention relates broadly and generally to the rotary type of printing platen mechanism, hence only such prior art, as may be necessary to establish a satisfactory matrix will be described. It relates particularly to platens such as those disclosed in connection with mechanism of patents to Lasker 1,317,509, dated September 9, 1919, 1,571,955, dated February 9, 1926, 1,627,394, dated May 3, 1927, 1,920,993, dated August 10, 1933, to Last 1,849,494, dated March 15, 1932 and Lasker's copending application Serial No. 684,438, filed August 9, 1933, but its use is not so restricted.

The invention is directed to overcome the uneven feeding of paper as it passes around the platen and certain objectionable features which attend adjustment and maintenance. It is well known that difficulty arises in securing even feeding of paper around rotary platens whenever the paper, or papers, being fed are of non-uniform thickness. This fault in the feeding necessitates the expenditure of considerable time in "truing up" the paper. Usually the tension on the respective pairs of feed rolls is supplied by springs attached to each of the pairs and anchored to the plate which supports the platen. Such spring arrangement is non-adjustable and cannot be repaired without dismantling the entire platen.

One object of the present invention is to make general improvements in the paper feeding mechanism in machines using rotary type platens.

Another object is to assure even feeding of the paper as it passes over the platen.

Another object is to provide a new and improved form of feed roll tensioning mechanism.

Another object is to provide novel means for equalizing the tension on the feed rolls.

Another object is to provide readily adjustable means for varying the feed roll tension between different points on the platen.

Another object is to provide novel changes in construction whereby satisfactory operation is more readily maintained.

Another object is to provide features whereby the mechanism is more readily accessible for repair.

The present invention relates to a novel arrangement of mechanism for supporting, guiding and controlling feed rolls which feed the paper around the printing platen of tabulating machines, typewriters, typewriting-bookkeeping machines, typewriting-addition machines, addition machines and other similar machines using ro-

tary type platens, and comprises means whereby the tension on the feed rolls may be automatically equalized to assure even feeding of paper of varying thickness or papers of various thickness; whereby the feed roll tension may be adjusted without disassembling the platen unit and whereby the spring member of the tension mechanism may be replaced without disassembling the platen unit.

Other objects and structural details of the invention will be apparent from the following description when read in connection with the accompanying drawings which form a part of this specification, and in which:

Fig. 1 is a perspective view of a platen supporting plate, platen drive mechanism, one platen roll of a split platen unit and the mechanism of this invention.

Fig. 2 is a fragmentary view of a platen supporting plate showing a complete unit of the mechanisms of this invention mounted thereon.

Fig. 3 is a view of a section through the mechanism of Fig. 2 taken on the line 3—3.

General description

The present invention contemplates the combination of means hereinafter to be fully described, and a rotary platen of standard construction and operation.

The mechanism comprises a supporting plate 1, supporting brackets 2, platen 3, feed rolls 4 and 4a, and the feed roll tension mechanism which will be described in detail hereinafter. The platen may be one continuous cylinder mounted according to any of the usual methods; or, it may be a so-called split platen, one element of such a platen being shown in Fig. 1. The feed roll tensioning mechanism consists of supporting brackets 11, control links 12, links 13, short equalizer bars 14, long equalizer bars 15, retaining plates 16, bell cranks 17, springs 18, and shafts 21 and 22, together with such screws, rivets, pins, washers, collars and spacers as may be necessary for proper assembly.

A pair of feed rolls 4 and 4a are journaled at opposite ends of a pair of arcuate supporting brackets 11. The supporting brackets 11 are journaled at their mid-points to the control links 12 which are suspended from the shaft 21. Links 13 connect control links 12 to equalizer bars 14 which are pivoted at their mid-points to equalizer bars 15, which latter are similarly pivoted at their mid-points to the horizontal arms of the bell cranks 17. Retaining plates 16 restrain and guide the assembled equalizing mechanism which

resembles the well known wagon-whiffle tree in its construction.

The shaft 22, journaled in hangers 23 and under control of a manipulative lever, (not shown), 5 acts upon projections 24 on the control link 12. Shaft 22 is milled to provide a flat surface which is maintained in contact with projection 24 by the spring action of member 18. Movement of the lever causes shaft 22 to exert a cam action against 10 projection 24 and remove the feed rolls 4 and 4a from contact with platen 3.

Feed roll tensioning

The paper is inserted between the feed rolls 4a 15 and the platen 3; and the platen is turned counterclockwise, as viewed in Fig. 3. The presence of this paper causes each feed roll assembly, consisting of members 4, 4a, and 11, to be displaced downwardly. This downward movement causes 20 tension to be applied to a set of elements, consisting of control links 12 and connecting links 13. Two sets of these elements are associated with each of the short equalizer bars 14. The motion of the bars 14 is transmitted to the long 25 equalizer bars 15, and thence to the horizontal arm of one or the other of the bell cranks 17. The movement of the bell cranks causes the respective vertical arms thereof to move in directions opposite to each other, which latter motion 30 is restricted by the spring 18.

It is apparent that even through the paper may 35 be of varying thickness the rolls will adjust themselves in such a way as to exert a uniform pressure against the platen, since the tension upon all rolls is exerted by one spring.

The tension may be varied by moving the spring 18 upwardly or downwardly along the notched vertical arms of the bell cranks 17. The amount of tension varies according to the distance of the 40 spring 18 from the fulcrum of the bell crank 17. Hence, if light pressure is desired at one end of the platen, the anchor point of the spring 18 is moved downwardly on that bell crank 17 which is associated with those feed rolls at the end 45 where the decreased pressure is desired.

When the necessity for renewing the spring 18 arises it may be removed from its mounting through the aperture 19 and a new spring inserted

and hooked on to the bell cranks 17. The notches on the outward sides of the bell cranks afford means for retaining the spring 18 in any position in which it may be set.

While I have described what I consider to be 5 a highly desirable embodiment of my invention, it is obvious that many changes in form could be made without departing from the spirit of my invention, and I, therefore, do not limit myself to the exact form herein shown and described, 10 nor to any thing less than the whole of my invention as hereinbefore set forth, and as hereinafter claimed.

What I claim as new and desire to secure by 15 Letters Patent, is:

1. In a device of the character described, a platen, a plurality of feed rolls, pairs of said rolls being journaled in parallel relation in arcuate side members, connecting means for pivotally securing said side members to the ends of a pair of 20 whiffle tree members, each of said whiffle trees being pivotally secured to one leg of an L-shaped arm, said L-shaped arms being pivotally mounted on a frame, a tension spring connecting the other legs of said arms to maintain said feed rolls in 25 equalized pressure engagement with said platen, and camming means acting on said connecting means for moving said rollers out of engagement with said platen.

2. In a device of the character described, a 30 platen, a plurality of feed rolls mounted in pairs parallel to the transverse axis of said platen, an equalizing means for said rolls comprising an arcuate carriage for each pair of rolls, said carriage being pivotally mounted in a train of links 35 secured to each end of a pair of a whiffle tree members, said whiffle trees being pivotally mounted on one end of a pair of L-shaped arms which are pivotally secured to a frame, a tension spring connecting the other leg of said arms to 40 maintain said feed rolls in equalized frictional engagement with said platen and a shaft, having cam faces thereon running parallel to said platen and journaled on said frame and co-operating with an arm on one of said train of links for each 45 of said carriages to effect the withdrawal of said pressure rolls from said platen.

ELMER H. DREHER.
